respectively and pressure members 50 and 60 then come to bear against the folded end 18, as shown in Figure 4. Of these, the upper member 60 which is directly in contact with the end 18 is heated and thereby seals the wall 20 to the wall 22 which, in turn, is sealed to itself, leaving the relatively open and accessible passageway 26.

As a matter of machine timing, the upper presser bar 60 will arrive at a position in which it will prevent re-folding of the end 18 while there is still a slight overlapping of the members 36 and 40. These members 36 and 40 then complete their withdrawing motions while the pressure member 60 descends to complete the seal.

It will be noted that the presence of the former plate 38 prevents sealing or blocking of the interior of the bag in the area in which member 60 seals the end 18. This materially increases the capacity of the bag and represents the outstanding reason why it is preferable to form the improved closure during manufacture where the structure of the machine permits the seal to take place while the interior is shielded. If the bag has been filled and the improved closure is applied as a "top" closure there would be no way to shield the interior of the bag, and blocking would inevitably occur in the area 24. It should be noted that this affects only the capacity of the bag and does not affect the functioning of the loop or passage 26 at the bag end.

The display rack heretofore described is the one in most common use. In certain sections of the country, however, a different form is used and bags sold in these territories should be designed for coaction with such racks. The two structures are, of course, independently usable, but for convenience of manufacture it is desirable in many cases to provide the bags with both features so that a given bag may be used with either form of display rack.

Such a bag is illustrated in Figure 5. In this figure there is shown a bag 100, having a front wall 102 and a rear wall 104. At one end, the front and rear walls are folded along two distinct score lines 106 and 108 to provide a two ply portion 110 extending generally normal to the plane of the walls 104 and 102. This structure would result from making the end 31 of the member 36 in Figure 3 rectangular instead of round as shown.

The end 106' of the wall 104 and the end 102' of the wall 102 are folded back against the wall 104 along the score lines 106 and 108. While in this position heat and pressure are applied, by members such as 50 and 60 illustrated in Figure 4, to the stippled area 112. The application of heat and pressure, however, is regulated so that end 102' is sealed to end 106' throughout the area 112, while the end 104' is sealed to the wall 104 only in that portion of the area 112 extending inwardly from the edges of the bag to lines *f-f* and *h-h*, respectively. This leaves the portion of ends 102' and 104', between lines *f-f* and *h-h*, completely free of wall 104, while the bottom of the bag is completely closed due to the seal between ends 102' and 104'.

A display rack hook may be inserted in the channel between end 104' and wall 104 and between lines *f-f* and *h-h*, in which case the hook will bear against the portion 110, which portion will directly support the weight of the package. This is enormously stronger support than is afforded by prior art structures in which the weight of the package is supported by a seal between the end 104' and the wall 104 which seal, extending

between lines *f-f* and *h-h*, would define a pocket rather than a channel. In addition to an increase in strength, the cost of the bag is materially lowered due to the fact that a narrower turnover in material at the end is required when it is not necessary to allow for a seal between the end of the bag and the pocket between the lines *f-f* and *h-h*. Under prior art practice, the edge 114 would have to extend to line L-L, Figure 10, 5, to accommodate such a seal.

It has been found that the portion 110 defined by score lines 106 and 108 offers considerable resistance to crushing of the loop at the bag end during stacking and shipping. Such anti-crushing tendency is enhanced when the bags are stacked end to end, that is, with the open mouth of one bag adjacent to the terminus 114 of the end fold of the next adjacent bag.

The terms "top," "bottom," "front" and "rear" 20 as used herein are intended purely for the purpose of reference in differentiating elements of the bag and are not intended to have any functional significance such as ordinarily attaches to these terms. While for simplicity of illustration, 25 this invention has been described with reference to flat bags, it is clear that every principle herein discussed is equally applicable to gusseted bags. The invention has also been described primarily with reference to heat sealing and it is in that 30 connection that the invention will have its greatest utility. It is, however, perfectly feasible to apply the principles herein discussed to pasted bags. The claim, therefore, shall be taken to include gusseted bags and pasted closures.

35 I claim:

A bag comprising: a flattened tube formed of 40 moisture-proof, flexible material, the walls of said tube being sealed together at one end to form a closure, the sealed closure being turned against the body of the tube to form an open, crease-free loop forming a relatively narrow channel across 45 the entire width of the tube, said closure being secured to the body of the tube in areas spaced longitudinally of the tube from the turned extremity of the tube so as not to obstruct the narrow channel defined by said loop and being mutually spaced on opposite sides of the center line of the tube to define between themselves, the tube body and said closure a relatively broad channel 50 communicating with said relatively narrow channel, said narrow channel being sized to receive a supporting rod or wire of one type of display rack and said broad channel being sized to receive a supporting plate of a different type of 55 display rack.

HAROLD F. SHUMANN.
